CLAIM

The ornamental design for a rubber crawler, as shown and described.

DESCRIPTION

FIG. 1 is a front perspective view of a rubber crawler showing my new design;

FIG. 2 is a front view thereof, wherein the claimed rubber crawler can continue in directions above and below the portion illustrated;

FIG. 3 is a top view thereof, the bottom view being a mirror image thereof;

FIG. 4 is a right side view thereof, the left side view being a mirror image thereof;

FIG. 5 is a rear view thereof; and,

FIG. 6 is a cross sectional end view taken along line 6-6 in FIG. 2.

The broken lines in the drawings illustrate features of a rubber crawler that are not being claimed, and form no part of the claimed design.
